[57] ABSTRACT

This invention relates to an improved traffic control sign. More particularly, it relates to a sign which contains a plurality of panels which are hinged together to expose a message in one position and to hide that message and/or expose a second message in the other position.

TRAFFIC CONTROL SIGN

CROSS REFERENCE TO RELATED PATENT AND APPLICATION

This invention is an improvement on my U.S. Pat. No. 3,394,674, entitled "TRAFFIC SIGN" issued July 30, 1968, and is a continuation-in-part of my copending application Ser. No. 277,668, filed Aug. 3, 1972, entitled "TRAFFIC CONTROL SIGN" now U.S. Pat. No. 3,741,147. My copending application Ser. No. 277,668 now U.S. Pat. No. 3,741,147 is incorporated into this application by reference.

BACKGROUND OF THE INVENTION

This invention is in the field of improved traffic control signs. More particularly, the invention relates to a sign for use in traffic control or the like, including means whereby upon actuation, the sign unfolds one or more hinged wings or panels to display a traffic directory signal, and upon subsequent actuation, folds the wing, or wings, to conceal the message or to display a different message. In the prior art as represented by my U.S. Pat. No. 3,394,674, a motor is provided to actuate the rotation of two wing panels which are attached at either side of a central rectangular panel so that when the wings are opened a prerecorded message is visible, and when the wing panels are closed, that is, folded over in contiguous position across the front of the central panel the message is covered. In general, the wings are preferably approximately half the width of the central panel, so that in the closed position no portion of the face of the panel is visible. As will be indicated in this application the device may consist of more than two hinged panels for the preparation of large message areas.

SUMMARY OF THE INVENTION

It is a principal object of this invention to provide a means by which the side or wing panels can be actuated by motor means as in U.S. Pat. No. 3,394,674, but to provide a flexibility in the operating means so that vandals who attempt to open the wings after the motor has closed them, will be prevented from breaking the fastening of the wings to the hinge shaft and vice versa when the wings are open. It will permit movement of the wings without breaking any part of the mechanism.

In the prior invention disclosed in U.S. Pat. No. 3,394,674, and application Ser. No. 277,668, now U.S. Pat. No. 3,741,147, a chain member operates a sprocket which is attached firmly to the hinge shaft, to which the wing panels are fastened. When the motor drive turns the sprocket and the shaft, the wing panel will be either in an open position or closed position. Torque applied to the wing panel would therefore be transmitted directly to the drive mechanism which because of its construction, did not permit rotation of the hinge shaft.

In this invention the sprocket rotates freely on the hinge shaft so that the motor drive simply operates the sprocket. There is a radial arm which is fastened to the sprocket and turns with it. There is a second radial arm which is spaced longitudinally from the first radial arm which is fastened rigidly to the hinge shaft. A helical spring surrounds the hinge shaft in the space between the two radial arms. One end of the spring operatively

presses against the first arm and the second end of the spring operatively presses against the second arm. As the sprocket is turned by the drive motor, the first arm turns with the sprocket causing the first end of the spring to move with it. The second end of the spring, because of the torque in the spring, moves in the same direction. This causes the second arm to move and therefore to rotate the wing shaft and with it the wing panel. In this construction since the wing panel is not connected rigidly to the sprocket of the drivemotor, it can be forced to rotate against the torque of the helical spring. Therefore, when undue pressure is applied to the wing panel, causing it to be rotated with the wing shaft or hinge shaft, it can rotate without breaking any part of the mechanism. The torque of the spring is sufficient so that the wing panels will follow the rotation of the sprocket as in the earlier invention. However, when undue force is offered against rotation the drive means can rotate without breaking any connection between the sprocket and the wing panel.

In the prior copending application Ser. No. 277,668, now U.S. Pat. No. 3,741,147, the operation of the sprockets is by means of a chain which links the sprockets. The chain is driven by a hinged arm which is controlled by a crank arm on a motor shaft. As the chain is transported longitudinally the two sprockets are turned and with them the corresponding hinged panels.

In this application there are shown some improvements in construction of the spring-controlled-hinge-sprocket system, but principally the improvement lies in the drive means between the hinge shafts or wing shafts and the drive motor. These are arranged by means of rack and pinion drives, or gear drives, involving a large gear sector rotating in contact with a small gear on the hinge shafts, the larger gears controlled by means of the crank shaft driven by the motor.

BRIEF DESCRIPTION OF THE DRAWINGS

These and other objects of the invention and a better understanding of the principles and details of the invention will be evident from the following description taken in conjunction with the appended drawings, in which:

FIGS. 1 and 2 represent plan and elevation views of the drive mechanism of this invention.

FIG. 3 illustrates in cross section the details of the drive system for one wing panel.

FIG. 4 is taken from prior art U.S. Pat. No. 3,379,674, and shows the general configuration of the sign.

FIGS. 5, 6, 7, 8, 9, 10 and 11 show various configurations of rack and pinion drives for the wing panel hinge shafts.

FIG. 12 indicates the use of the chain and sprocket system for a larger plurality of hinge shafts.

FIGS. 13, 14, 15, 16 and 17 indicate a plurality of embodiments involving gear sectors and pinions in conjunctions with crank arms to rotate the hinge shafts.

DESCRIPTION OF THE PREFERRED EMBODIMENT

Referring now to FIG. 4 which represents the prior art as described in U.S. Pat. No. 3,394,674, the sign of this invention is indicated generally by the numeral 10. The sign is supported on a post 12 or by other means. It consists basically of a rectangular vertically sup-

ported planar center panel 14 presenting a sign bearing face on one side thereof, adaptable to have a portion of the traffic control message printed thereon.

There are first and second rectangular planar wing panels 16A and 16B each pivotally supporting at a vertical edge to the two opposite vertical edges of the center panel, at hinges 13A and 13B. An actuating mechanism is contained in a covered enclosure 18 on top of the sign. This mechanism rotates the wing panels 16A and 16B to a first position shown in FIG. 4 where they are coplanar with the center panel 14, to display a traffic control message printed across the three coplanar panels 16A, 14 and 16B. The second position is not illustrated but is the condition where the wing panels are rotated 180° about their hinged edges 13A, 13B, and are folded over, in contiguous parallel positions with the center panel. In general, the width of the wing panels 16A, 16B is substantially one-half the width of the center panel 14, so that the two wing panels completely cover and hide the message printed on the inner faces of the three panels.

As will be shown later in connection with other figures, this application cover variations of the design of FIG. 4 wherein there are a plurality of spaced-apart fixed panels, with hinged panels in between. The assembly may also be simply a plurality of spaced hinged panels so that when they are exposed in one position they will show one message and after being turned 180° they will expose a second message and so on.

FIGS. 1 and 2 are substantially the same as the correspondingly numbered figures in application Ser. No. 277,668, now U.S. Pat. No. 3,714,417. Since that application is made a part of this application by reference, the full detail of the construction of the apparatus of FIGS. 1 and 2 will not be repeated and reference is made to the application Ser. No. 277,668, now U.S. Pat. No. 3,714,417.

Very briefly, there are two hinge assemblies or systems, indicated generally by the numeral 15, mounted at opposite ends of the top plate 23 of the housing 18. The construction of these hinge assemblies is shown in FIG. 3 and will be described in detail. In the prior application there are sprockets 30A and 30B mounted on each of the hinge units which are connected by chain 32 with corresponding mechanical links 35A, 35B, 34B, 32A, etc. which are controlled by the rotating arm 42 which is controlled by the link 48 from a crank pin 50 on a disc 40 which is driven by motor 36 through shaft 38.

Referring to FIG. 3 there is a tubular bushing 70 which is fastened by means 72 to the plane 23 which forms the base of the housing 18. This bushing 70 forms an inner bearing surface for the support of the hinge shaft, or wing shaft 74, which drives the wing panels by means of threaded holes 76 and screws, etc., not shown. Also, rotating on the outside surface of the bushing 70 is a sprocket 30 pinned by 79 to arm 78. There is a squared portion 86 on the top end of the hinge shaft 28, which drives an arm 82, 88 which is held in position by screw 81. There is a tube 71 rotatable on bushing 70 which supports a helical spring 90, which has two ends 92 and 94, which extend in substantially the same direction from the axis and press on opposite sides of the two arms 78 and 88. If one arm, 78, rotates with respect to the other arm 88, it tends to drive one end or the other, 92 or 94, and to spread the ends of the helical spring. This will apply torque to the other

end 94 or 92, as the case may be, and cause the second arm to follow the rotation of the first arm.

This action is similar to the assemblies shown in FIG. 3 of the application Ser. No. 277,668, now U.S. Pat. No. 3,714,417, but has a simplified and improved construction.

Reference will now be made to the drawings 5, 6, 7, 8, 9, 10 and 11 which represent a number of different configurations in which the hinge shafts 74 are driven in rotation, either clockwise or counterclockwise, by means of a plurality of linear gear racks, such as 55A, 55B, cut on a linear member 51, and running in contact with pinions 30A and 30B, supported on the spring assemblies 15. The linear member 51 is guided by means of pins or rollers 53 so as to move longitudinally, and remain in operative contact with the pinions. These pins or rollers are indicated in some of the views. However, whether shown or not, some such guiding means as that shown in FIG. 5, for example, well known in the art, is understood to be present in each of the FIGS. 5-11.

In FIG. 6 the linear member 51' differs from that 51 in FIG. 5, in that the racks 56A and 56B are cut on opposite edges of the member 51'. Thus, as it moves longitudinally in one direction the pinions 30A and 30B are rotated opposite directions, whereas in FIG. 5 they were rotated in the same direction. In both FIGS. 5 and 6 the linear member 51, 51' can be moved longitudinally by means of a pivoted arm 49 hinged at axis 46, and driven by crank arm 48 from the disc 40 driven by the motor. The contact between arm 49 and the member 51 can be a direct mechanical contact whereby the arm 49 fits into a slot or similar means on the member 51, or it can be through the medium of springs 41 tied, each with one end on the member 51, and the other end at point 45 on the arm 49.

In FIGS. 7 and 8 there is a similar situation between the two figures, as between FIGS. 5 and 6, in that in FIG. 7 the hinge shafts rotate in opposite directions, whereas in FIG. 8 they rotate in the same direction. The drive is by direct contact between the arm 48 and the moving member 58 in FIG. 7 and 58' in FIG. 8. In FIG. 8 the arm 48 operates on a rigid side arm 54 attached to the member 58' at point 59.

Referring to FIGS. 10, 11, there is great similarity of FIG. 10 with respect to FIG. 7, and FIG. 11 with respect to FIG. 8, in that alternate hinge shafts rotate in opposite directions in FIG. 10, and the same direction in FIG. 11. In FIG. 10 the member 58'' is a summation of a plurality of members 58 of FIG. 7. Similarly, the member 51'' is a plurality of members such as 58' of FIG. 8.

FIG. 9 differs slightly from these other figures although it operates on the same rack and pinion principle. There is a hinged arm 62, rotating about pivot 63, and there are two members 68 and 69 which carry gear racks 73A and 73B respectively which mesh with pinions 30A and 30B. By rotation of the wheel 40 this arm 62 rotates about the hinge point 63, moves the racks in opposite directions and causes rotation of the pinions in opposite directions.

FIG. 12 indicates schematically a situation similar to that of the chain system in FIG. 1 except that it operates with a larger plurality of sprockets and of hinge shafts 74. Referring now to FIGS. 13 and 17 there are a plurality of assemblies in which a pinion is mounted on each of the hinge shafts 74. These are driven by gear

sectors 20A, 20B, for example, which are hinged at points 22A and 22B and are driven as in FIG. 1 by links 48A and 48B, which are driven by a crank arm on the disc 40. In FIG. 13 the two sectors rotate in the same direction simultaneously. In FIG. 14 the two arms 48A and 48B are driven in opposite directions by means of the gears 26A and 26B driven by pinion 24 on the motor shaft.

FIGS. 14 and 15, while they have essentially the same apparatus, have a different starting point so that whereas FIG. 14 operates the two pinions in opposite directions, FIG. 15 operates them in the same direction. By relatively rotating pinion 26B by 180° the same operating condition is obtained as in FIG. 14. FIG. 15 is similar in operating characteristics to FIG. 13.

FIG. 16 is similar to FIG. 13 in that, in effect, a single link 25 which is substantially the same length as links 48A and 48B together, connects the two gear sectors 20A and 20B. The system is driven by a crank arm 48 from the disc 40.

FIG. 17 is similar to FIG. 16 except that the arm 25 is connected to the sector 20A' at a point 27A which is on the opposite side of the pivot 22A than is the point 27B. Thus, as the crank disc 40 rotates, and arm 48 pulls the point 27B in an oscillating manner, the two gear sectors 20A' and 20B' will rotate in opposite directions and the pinions will rotate in opposite directions.

While a number of examples of drives utilizing linear gear racks and curved gear racks, or gear sectors, have been shown, controlled by crank arms and crank means, it will be clear that there are other possible examples of such mechanisms, and those which are indicated are simply shown as samples of possible mechanism. It is intended in this application to cover any operating system whereby a motor driven crank shaft rotating substantially 180° will operate the hinge shafts of a plurality of panels in a corresponding manner through angles of 180°, or thereabouts.

While the invention has been described with a certain degree of particularity it is manifest that many changes may be made in the details of construction and the arrangement of components. It is understood that the invention is not to be limited to the specific embodiments set forth herein by way of exemplifying the invention, but the invention is to be limited only by the scope of the attached claim or claims, including the full range of equivalency to which each element or step thereof is entitled.

What is claimed:

1. In a traffic control sign including:
a first rectangular planar panel and means to support said first panel in a vertical position;
at least a second rectangular vertical planar panel, means to rotatably support said second panel at a vertical edge thereof to a vertical edge of said first panel, said second panel rotatable;
means to support electric motor means on said first panel;
means to support a support plate on said first panel and means to journal wing shaft means in said support plate, said second panel attached to said wing shaft means;
means to rotatably mount wing shaft drive means about said wing shaft;
drive means operatively connected between said motor and said wing shaft drive means;

means for controllably starting and stopping said motor, wherein upon energization of said motor in one instance said wing shaft and said rotatable panel are rotated in one direction, and upon subsequent energization of said motor in a second instance they are rotated in the opposite direction; the improvement comprising:

spring drive means operatively connected between said wing shaft drive means and said wing shaft means comprising:

- a first radial arm attached to said wing shaft drive means, said wing shaft drive means rotating freely coaxial with said wing shaft;
- a second radial arm, spaced along said wing shaft from said first arm, attached to said wing shaft;
- helical spring means surrounding said wing shaft in the space between said radial arms, first and second ends of said spring means operatively connected to said first and second arms;

whereby when said wing shaft drive means is actuated, said first arm will rotate, causing one end of said spring to be rotated, causing said second end of said spring to be rotated in the same direction, and causing said second arm to be rotated, causing said wing shaft and said rotatable panel to be rotated.

2. A traffic control sign as in claim 1 including two rotatable panels, and means to rotatably support each panel at one vertical edge thereof to opposite vertical edges of said support panel.

3. The traffic control sign as in claim 1 including more than two spaced hinged rotatable panels.

4. A traffic control sign according to claim 2 including:

a traffic control message imprinted on the back surfaces of said two rotatable panels, whereby when said rotatable panels are closed upon said supported panel, said traffic control message imprinted upon the back surface of said rotatable panels is displayed.

5. A traffic control sign according to claim 1 wherein said means of controllably starting and stopping said motor includes:

switch means having electrical connection with said motor; and
cam means driven by said motor actuating said switch means in response to the angular position of said wing shaft drive means.

6. The traffic sign as in claim 1 in which said wing shaft drive means includes sprocket and chain means.

7. A traffic control sign according to claim 6 wherein said drive means coupling said motor and said wing shaft drive means includes:

rocker arm means pivotally supported at one end and affixed to a chain means coupling said sprocket means, at the other end, whereby the pivot of said rocker arm transports said chain;
crank shaft means extending from and rotated by said motor; and
connecting arm means having one end pivotally affixed to said crank shaft means and the other affixed to said rocker arm means.

8. The traffic sign as in claim 1 wherein said wing shaft drive means includes pinion means.

9. The traffic sign as in claim 8 wherein said drive means coupling said motor and said wing shaft drive means includes linear rack means.

10. The traffic sign as in claim 8 wherein said drive means coupling said motor and said wing shaft drive means includes rotatable gear sector means.

11. The traffic sign as in claim 8 including means to

rotate a plurality of said wing shaft means in the same direction.

12. The traffic sign as in claim 8 including means to rotate more than two of said wing shaft means in opposite directions.
